UNITED STATES PATENT OFFICE.

PHILOMENE FERRIS, OF WESTWOOD, CALIFORNIA.

SHOE-FASTENER.

1,348,703.

Specification of Letters Patent. Patented Aug. 3, 1920.

Application filed January 23, 1920. Serial No. 353,442.

To all whom it may concern:

Be it known that I, PHILOMENE FERRIS, a citizen of the United States, and a resident of Westwood, in the county of Lassen and State of California, have invented a new and Improved Shoe-Fastener, of which the following is a full, clear, and exact description.

This invention relates to improvements in shoe fasteners, an object of the invention being to provide a shoe with a series of independently operated fastening devices which can be conveniently attached or replaced when worn or broken and which will permit the shoe to be secured around the ankle and foot to conform to the shape thereof by reason of the fact that the individual fasteners can be adjusted so that they may be of varying lengths at different points on the shoe.

A further object is to provide an improved shoe fastener which can be conveniently and quickly operated and which will be neat and attractive in appearance and most efficiently perform the functions for which it is intended.

With these and other objects in view the invention consists in certain novel features of construction, and combinations and arrangements of parts, as will be more fully hereinafter described and pointed out in the claims.

In the accompanying drawings—

Figure 1 is a perspective view illustrating a shoe provided with my improved fastening devices;

Fig. 2 is an enlarged view in elevation illustrating one of the fasteners shown in Fig. 1;

Fig. 3 is a view in section on the line 3—3 of Fig. 2; and

Figs. 4, 5; 6, 7; 8, 9; 10, 11; 12, 13 are views similar to Figs. 2 and 3 illustrating modifications.

1 represents a shoe which I have illustrated of the ordinary high shoe type, although it is obvious that my improved fasteners are adapted for use on low shoes or boots of any character. In Figs. 1, 2 and 3 I illustrate one form of my invention in which I employ flexible straps 3 which are permanently secured at one end to one side 4 of the shoe upper and are passed through loops 5 which are secured to the other side 6 of the shoe upper. The parts 3 I shall refer to as straps and would have

it understood that I employ this term in its broadest sense to indicate any form of flexible strip, cord, or other connecting device which could be used for the purpose. 60

The end of each strap 3 is secured to the side 4 by means of a rivet shank 7 of a headed button 8. The loop 5 of each fastening device is supported by a coupling 9 which may be of metal if desired, or of other suitable material, and said coupling or clip is secured by a rivet 10 or other approved connecting device to the side 6 of the shoe upper. The strap 3 is provided at its free end with a buttonhole 11 so that when the 70 strap is positioned through the loop 5, its end is connected over the button 8 to secure the same in position.

In the modification illustrated in Figs. 4 and 5, I employ the same loop 5 and its 75 connecting means, as shown in Figs. 1, 2 and 3, but connect the strap 3 with the side 4 of the shoe upper by means of an adjusting slide buckle 12, a clip 13, and a button 8 similar to the button of the preferred form. 80 The clip 13 is secured by the button 8 to the side 4 of the shoe upper and is connected to one end of the adjusting buckle 12, while the strap 3 is connected to the adjusting buckle and is capable of a longitudinal adjustment to give the desired length to the strap to exactly suit the user. This strap 3 is, of course, provided with a buttonhole 11 to engage the button 8.

In the modification illustrated in Figs. 6 90 and 7, I provide a fastener 14 which is provided with a loop 15 receiving and supporting the loop 5, and said fastener is provided with prongs 16 which are projected through the shoe upper to secure the fastener in 95 place. In this form of my invention I also provide an adjusting slide buckle 17 which has a recessed end 18 so that it can be removably positioned on the shank of button 8, thus enabling the strap 3 and its buckle 100 17 to be disconnected at will.

In the modification illustrated in Figs. 8 and 9, the structure is like that shown in Figs. 4 and 5 with the exception that I employ a fastening device 14 similar to that 105 shown in Figs. 6 and 7.

In Figs. 10 and 11, I illustrate a modification in which I employ the same structure of the strap 3 and its connecting means to the shoe upper as illustrated in Figs. 3, 4, 5 110 and 6, but employ in lieu of the loop 5 and its fastener a loop member 17 which is re-

movably connected to a button 18 on the shoe upper, and to facilitate the connection and disconnection of the loop member 17 I provide a recess 19 at one end of the loop member to engage the shank of the button 18.

In the modification illustrated in Figs. 12 and 13, I provide a loop 5 which receives the strap 3, the latter secured at one end to the side 4 of the shoe upper by means of a rivet 10 18 and at its other end provided with a buttonhole 20 to receive a button 21 also on the member 4. The loop 5 is supported by a tab 22 having a buttonhole 23 therein which is removably supported by a button 24 on the 15 side 6 of the shoe upper.

It will be noted that with all forms of my invention I provide a flexible strap or other similar means which is connected at one end to one side of the shoe upper, which is passed 20 through a loop or other similar device on the other side of the shoe upper, and which is removably connected at its end to the same side of the shoe upper to which its other end is connected.

25 I have illustrated certain of the straps as provided with adjusting means which permit the several straps to be of different lengths, and hence, insure the proper fitting of the shoe upper to the foot and ankle, and I have 30 illustrated certain of the forms in which the strap is removable as an entirety or the

whole fastener removable as in Figs. 10, 11, 12 and 13.

It is obvious that other modifications might be made in the general form and arrangement of parts described without departing from my invention, and hence I do not limit myself to the precise details set forth, but consider myself at liberty to make such changes and alterations as fairly fall 35 40 within the spirit and scope of the appended claims.

I claim:

1. The combination with a shoe, a series of independent loops secured to the outer face 45 of the shoe upper at one side thereof, a series of straps connected to the shoe upper at the other side thereof, said straps adapted to be positioned through the loops, and means removably connecting the free ends of said 50 straps to the same side of the shoe with which they are secured.

2. A shoe fastener, comprising a loop, means for securing the loop to the outer surface of one side of the shoe, a flexible 55 connecting member having one end secured to the outer surface of the other side of the shoe, and means for removably securing the free end of the flexible member after it is passed through the loop.

MRS. PHILOMENE FERRIS.
